UNITED STATES PATENT OFFICE.

SAMUEL T. WHITAKER, OF COLUMBUS, GEORGIA, ASSIGNOR OF ONE-HALF TO HOMER C. McCUTCHEON, OF COLUMBUS, GEORGIA.

SANITARY DRINKING APPARATUS.

1,213,319.

Specification of Letters Patent. Patented Jan. 23, 1917.

Application filed September 15, 1916. Serial No. 120,260.

To all whom it may concern:

Be it known that I, SAMUEL T. WHITAKER, a citizen of the United States, residing at Columbus, in the county of Muscogee and 5 State of Georgia, have invented certain new and useful Improvements in Sanitary Drinking Apparatus; and I do hereby declare the following to be a full, clear, and exact description of the invention, such as 10 will enable others skilled in the art to which it appertains to make and use the same.

This invention relates to improvements in drinking apparatus, and the object in view is the assurance of a sanitary condition during the operation of drinking directly from 15 a bottle.

With this and further objects in view, the invention comprises certain novel constructions, combinations and arrangements 20 of parts as will be hereinafter specified and claimed.

In the accompanying drawing,—Figure 1 is a vertical central section through an apparatus embodying the features of the present 25 invention and illustrated as applied within the neck of a bottle, portions of the bottle being broken away. Fig. 2 is a perspective view of the apparatus.

Referring to the drawing by numerals, 1 30 represents an upper tubular portion, and 2 a lower tubular portion of a drinking apparatus adapted to be applied directly to the neck of a bottle 3. Each of the tubular portions 1 and 2 is formed at the end adjacent 35 the other tubular portion with an outstanding annular flange 4 and between the flanges is arranged a filter or screen 5. The flanges 4 may be connected together in any appropriate manner but preferably by a covering 40 sheet 6.

In practice it is preferable to form the tubular portions 1 and 2 with their flanges 4 of paper and the sheet 6 is also preferably formed of paper and is connected to the 45 flanges by any appropriate adhesive. Of course, the structure may be formed of papier-mâché and compressed into shape in which instance the tubular portions and flanges would all be formed integral, and 50 the screen 5 would be positioned during the course of formation of the structure.

It is desirable that the tubular portions 1 and 2 shall be duplicates of each other so

that either may be introduced into the throat of the bottle and the other left protruding. 55 Of course, the statement that the tubular portion 1 extends upward and the portion 2 downward is merely relative and refers to the position assumed as shown in the drawing. 60

It is apparent, of course, that the flange formed midway of the entire tubular structure as a result of the presence of the flanges 4 and their engaged ends may vary materially in size and contour and various substitutes may be utilized within the spirit and scope of the invention. The principal function of the flange is to provide a stop to engage the upper end of the bottle neck. 65 The screen 5 may in some instances be omitted.

Each of the sections 1 and 2 is preferably tapered away from the central flange so as to facilitate introduction into the throat of the bottle and also to assure a snug fit 75 therein.

What I claim is:—

1. In sanitary drinking apparatus, a tubular structure having a lateral projection intermediate its ends adapted to engage the 80 upper edge of a bottle neck when the structure is introduced into the neck, the portions of the tube extending in opposite directions away from the projection being substantially duplicates of each other and each 85 adapted to snugly fit within a bottle neck.

2. In sanitary drinking apparatus, a tubular structure having a lateral projection intermediate its ends adapted to engage the upper edge of a bottle neck when the structure is introduced into the neck, the portions of the tube extending in opposite directions away from the projection being substantially duplicates of each other and being tapered in directions away from the projection 90 for enabling each to snugly fit within a bottle neck.

3. In sanitary drinking apparatus, tubular aligned sections each a substantial duplicate of the other and each comprising a tapered body having a terminal flange, and means connecting the flange for producing a lateral projection in the length of the completed structure, each section being proportioned to fit within a bottle neck. 100

4. In sanitary drinking apparatus, a tu- 105

bulular structure having an annular shoulder adapted to rest on top of a bottle neck in position for having a portion of the tube extend into the bottle neck and a portion of the tube extend upwardly beyond the bottle neck, the former portion being adapted to snugly fit within a bottle neck.

In testimony whereof I affix my signature in presence of two witnesses.

SAMUEL T. WHITAKER.
